GRINDING WHEEL EDGE DRESSER

William F. Dalzen, Lennox, Mich., assignor to Louella May Dalzen, William Russel Dalzen, and Frederick Roy Dalzen, all of Detroit, Mich., as trustees

Original application December 18, 1941, Serial No. 423,517, now Patent No. 2,341,022, dated February 8, 1944. Divided and this application January 8, 1944, Serial No. 517,599

1 Claim. (Cl. 125—11)

1

This is a divisional application of my pending application Serial No. 423,517, filed December 18, 1941, now Patent No. 2,341,022, dated February 8, 1944, relating to a Grinding wheel form dresser; reference being had to the accompanying drawing, forming part thereof.

This invention relates to a grinding wheel edge dresser, and more particularly to a dresser of this type adapted for use in conjunction with a thread grinding machine, wherein a work-piece is rotated and reciprocated on a suitable carriage past a rotatable abrasive grinding wheel with the cutting peripheral edge thereof cooperatively engaging transversely the surface of the work-piece for grinding a thread in the same.

From time to time the cutting edge of the grinding wheel is worn down, or is broken, or chipped requiring a re-truing or resurfacing.

It is the object of this invention to provide a novel grinding wheel form dresser adapted to produce various shaped surfaces in the edge of the abrasive grinding wheel for accurately grinding out various shapes of threads.

It is the still further object herein to provide a dresser for dressing the outer edge of the abrasive grinding wheel for providing thereon a curved surface, together with adjusting means for regulating the degree of curvature.

Other objects will be seen in the various arrangements of parts and combinations thereof as will be hereinafter described in connection with the appended drawing of which:

Fig. 1 is an elevational view of the grinding wheel edge dresser.

Fig. 2 is a sectional bottom plan view thereof.

The above drawing illustrates merely preferable embodiments of the invention, it being expressly understood that it is not intended that the invention be limited thereby.

In the drawing, the grinding wheel dresser supporting housing 11 is vertically and reciprocably mounted along its dovetail vertical edge 12 with respect to the vertically movable grinding wheel support of a thread grinding machine, said support and machine not being shown herein inasmuch as no claim is made thereto.

The grinding wheel 20, however, is fragmentarily illustrated in Fig. 1, it being understood that means may be provided for effecting adjustment of housing 11 and the edge dresser B thereon with respect to said grinding wheel. Such adjustment, forming no part of the present invention is, however, illustrated in the above referred to parent application, of which the present application is a divisional part.

2

The dressing mechanism consists of a base member 127 with a longitudinally and centrally disposed semi-circular slot 128 therein. Base member 127 is secured to housing 11 by a plurality of screws 129.

Member 127 longitudinally under-cut along lines 130 provides a dovetail support for the slide 131 disposed thereon. A threaded screw 132 with a handle 133 is longitudinally disposed through a flanged portion 134 of the base member 127. Said screw threadably engages slide member 131 and is adapted to cause reciprocation thereof upon member 127.

A bifurcated member 135 is secured upon said slide at points 136 and is adapted to move therewith. A diamond supporting slide member 137 is slidably disposed within said bifurcated member and is adapted for reciprocable movement therein with its bottom surface resting upon the upper surface of slide 131 with respect to which said slide 137 is transversely movable at right angles.

A screw member 138 with actuating means 139 is longitudinally disposed through support 135 and is in threaded engagement with slide 137 for causing reciprocation thereof with respect to member 135. An opening is provided through the outer end of slide 137 and has disposed therein bearing member 138' for journaling a rotary diamond support 139' with means 140 on the end thereof for manually rotating the same.

An adjustable diamond mounting 141 is disposed upon the end of rotary member 139' and is adapted to engage the outside peripheral edge 35 of the grinding wheel 20 when brought into co-operating engagement with respect thereto.

Stops 142 and 143 are angularly disposed transversely with respect to the rotary member 139' and are adapted to alternately engage the upper member 144' which is secured to slide 137.

In operation for accomplishing a curvature upon the grinding wheel 20 member 139' is manually rotated causing the diamond mounting 141 to engage the outer surface of said grinding wheel. The stops 142 and 143 with adjusting means 144 and 145 are adapted to limit the rotary movement of member 139'.

By actuating handles 133 and 139 it will be seen that the diamond mounting 141 is readily brought into proper engagement with the grinding wheel 20 for accomplishing the purpose above set out.

When inoperative the rotative diamond support 139' is partially removed from the bushing or bearing member 138' so as not to obstruct

3

the interior of the housing 11 or may be removed entirely.

Having described my invention reference should now be had to the claim which follows for determining the scope of this invention.

I claim:

A grinding wheel edge dresser comprised of a housing into which a grinding wheel is adapted to extend transversely, a manually adjustable horizontal slide on said housing, a manual vertically adjustable diamond mounting support with a transverse opening therethrough carried on said slide, a bearing provided within said

4

opening, a manually rotatable diamond mounting journaled within said bearing for arcuately dressing the outer periphery of a grinding wheel, an upright limit bar on said support spaced from and parallel to said mounting, relatively angular spaced arms extending transversely from said mounting, and adjustable screws on said spaced arms alternately engageable with said upright bar for adjustably limiting the dressing arc of said mounting, said diamond mounting being slidably insertable within said bearing permitting manual insertion and removal at will.

WILLIAM F. DALZEN.
